CIGARETTE PACKAGE OPENER

Henry N. Dreis, Duluth, Minn.

Application August 15, 1938, Serial No. 224,859

2 Claims. (Cl. 30—2)

This invention relates to package opening devices and is particularly adapted for use in connection with the opening of the conventional cigarette package.

Practically every brand of cigarette on the market today is wrapped in a package which includes layers of paper and metal foil with a revenue stamp sealing the top of the package and an outer cover formed from a sheet of transparent material usually formed from derivatives of cellulose, this outer wrapper being sealed and extremely resistant to tearing. To open such a package it is necessary to either laboriously remove the cellulosic outer wrapper by separating the sealed seams thereof or cut away a portion of the outer wrapper before the foil and paper can be opened up. Furthermore, it is common practice to tear away only a portion of the upper corner of the package to expose only a small part of the interior thereof with the result that the revenue stamp or seal is frequently left intact.

It is, therefore, a general object of my invention to provide improved means for quickly and simply cutting away portions of the outer wrapper and the main package to permit removal of the contents thereof and also to deface the revenue stamp so that it will be unfit for further use.

Another object of the invention is to provide means for holding the package rigidly during the cutting operation, but at the same time permit easy removal of the package from the device when the cutting operation has been completed.

A further object of the invention is the provision of a device which can be operated with one hand without removing the hand from portions of the package which are not being cut so that the entire operation is greatly simplified.

A still further object of the invention is the provision of means for receiving the cut away portions of the package along with cutting means which will positively direct these cut-away portions into the receiving means.

These and other objects and advantages of the invention will more fully appear from the following description made in connection with the accompanying drawing, wherein like reference characters refer to the same or similar parts throughout the views, and, in which:

Fig. 1 is a side elevation in vertical section showing the cigarette package and the package receiving means in an alternate position in dotted lines;

Fig. 2 is a section taken on the line 2—2 of Fig. 1;

Fig. 3 is a fragmentary section taken on the line 3—3 of Fig. 2, and

Fig. 4 is a plan view of the top of a package which has been opened by my improved cutting device.

In the drawing there is shown a base in the form of a receptacle having a vertical back 5, vertical side walls 6, a bottom 1, and a slanting forward wall 8. Extending outwardly from adjacent the side edges of the forward wall 8 are oppositely disposed channeled strips 9 which are adapted to act as guide ways. A package receiving element which includes the longitudinal sides 10 has ribs 11 extending along said sides and received within the channeled elements 9 in slidable relation thereto. The side walls 10 of the receiver are separated by brace elements 12 which slant downwardly toward opposite ends of the slidable package receiver and have disposed between them a pair of parallel transverse positioned package holding cross pieces 13, the latter being spaced to some extent from the outer face of the front wall 8 of the base receptacle. A helical spring 14 has one end secured to the underside of the slanting front face 8 of the base receptacle as by a screw 15, and the other end of said spring is secured to a screw 16 which is threaded into the inner edge of the lowermost of the package holding cross pieces 13. The spring is adapted to hold the receiver normally in the upper position shown in full lines in Fig. 1. The elongated slot 17 in the slanting front wall 8 permits movement of the screw 16.

The slanting front wall is provided with a rectangular cut-out 18, as best shown in Fig. 3, and a cutter blade 19 which is secured on the inner side of the slanting front wall 8 is curved outwardly and upwardly through said rectangular cut-out and thence for a short distance parallel to the outer surface of said slanting wall 8 a slight distance outwardly from the plane of said surface. It will be noted that the cutter 19 has a blade 20 which is formed on a diagonal line to assist in its cutting action. The cutter 19 as shown in the drawings is so positioned that when a package of cigarettes and the like is placed in between the package holding cross elements 13, and the package receiver as a whole is pulled downwardly said cutter will shear away a corner portion of said package along the lines shown in hatched section in Fig. 4.

The cutter 19 being positioned parallel to the end of the package in the receiver will, of course,

cut only vertical or substantially vertical walls of the package, and it is necessary to have a second cutter 21 which is positioned at right-angles to the cutter 19 in the manner indicated in the drawing to make a cut across the end of the package along the line 22 in Fig. 4. The cutter 21 is secured by a bolt 23 which extends through a block 24 suitably secured on the inner side of the slanting wall 8. In view of the fact that the edge of the cutter opposite to its sharpened edge rests against a shoulder 25 of the block 24 it is necessary to use only one cutter securing bolt to hold the cutter blade rigidly in its proper position. Of course, a slot 26 is provided through the slanting wall 8 to permit the cutter 21 to extend through said wall.

In parallel spaced relation to the slot 26 is a similar slot 27 through which projects a third cutting blade 28, the latter lying approximately along the longitudinal center of the slanting front wall 8. The cutter 28 is secured on the opposite side of the block 24 from the cutter 21 and is rigidly held by the bolt 23 in the same manner as said cutter 21. The cutting blade 28 is adapted to cut through that portion of the revenue stamp or seal 29, this cut being illustrated at 30 in Fig. 4. Thus the seal or revenue stamp is mutilated so that it cannot be used again. It will be noted in Fig. 1 that the seal cutting blade 28 is placed with its cutting edge at a slight angle with respect to the front face of the slanting wall 8, the upper portion of the edge of said blade being below the outer surface of said slanting wall, and the lower portion of the cutting edge of the blade being above the outer surface of said slanting wall 8. This provides for extremely efficient cutting of the package. It should also be noted that the spaced cutting blade 21 is held at a similar angle.

From the foregoing description it will be seen that when a package P is placed in the receiver between the cross members 13 and the entire receiver pulled downwardly against the action of the spring 14, the package will be cut in the manner indicated in Fig. 4 in but a single operation. It is necessary only to draw the receiver down, then release it and remove the package and an end portion of said package will be cut away and the seal or revenue stamp will be mutilated. That portion of the package which is cut away will be deflected by the curved portion of the cutter 19 and positively deflect into the interior of the waste receiving chamber formed between relatively stationary bases. This will prevent those portions of the package which have been cut away from falling to the outer side of the slanting front wall 8 and possibly jamming the slid-

able package receiver. To permit removal of waste from the interior of the stationary base one of the side walls 6 may have hinges 31 so that said base can be opened.

5 It will, of course, be understood that various changes may be made in the form, details, arrangement and proportions of the various parts without departing from the scope of my invention.

10 What is claimed is:

1. An opener for cigarette packages and the like comprising a box-like receptacle having a slanting face thereon, a pair of cutters supported by said receptacle adjacent said slanting face and positioned substantially at right-angles to each other, a cigarette package receiver slidably mounted on said slanting face, said receiver including a compartment adapted to hold a package of cigarettes and the like substantially at right-angles to said slanting face, said movable receiver being constructed to permit movement of a package to be opened to cutting engagement with said cutters, one of said cutters being so positioned relative to said movable receiver that it will engage and cut side wall portions of a package, and said other cutter being so positioned that it will come into cutting engagement with an end wall portion of said package and said cutters being so positioned relative to each other that the cuts in said package will intersect.

2. An opener for sealed cigarette packages comprising a trackway, a package holder supported by said trackway for movement relative thereto, a substantially vertical cutting blade disposed longitudinally of said trackway and spaced inwardly a short distance from a side thereof, said cutting blade having its edge portion disposed at an incline to said trackway, said inclined cutting edge being so positioned as to engage a cigarette package moved in said holder between the ends of said cutting edge and to penetrate only a sufficient distance into said package to cut its walls, and a second cutting blade rigidly mounted with respect to said first cutting blade and supported by said trackway, said second cutting blade being disposed at a plane normal to that of said first cutting blade and having its cutting edge portions extending only between the line of said first cutting blade and the adjacent side of said trackway, the cutting edges of said second blade being disposed at an angle to a line transversely of said trackway, and the cutting edges of said second blade being disposed at substantially the same relative height as the higher end of said inclined first cutting blade.
